Primary Examiner — Holly H. Baynam*Assistant Examiner* — Michelle E Wilson(74) *Attorney, Agent, or Firm* — Knobbe, Martens, Olson & Bear, LLP(57) **CLAIM**

The ornamental design for a diaper, as shown and described.

DESCRIPTION

FIG. 1 is a rear elevation view of a diaper embodying my new design.

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, rear, and left side perspective thereof; and,

FIG. 8 is a folded and front elevation view thereof in an alternate position with the diaper folded in an example usable configuration including showing a front portion folded over itself.

The broken line showing of button features is included for the purpose of illustrating environment and forms no part of the claimed design.
